UNITED STATES PATENT OFFICE.

FRANK R. MILLER, OF TROY, OHIO, ASSIGNOR TO THE HOBART MANUFACTURING COMPANY, OF TROY, OHIO, A CORPORATION OF OHIO.

FOOD-TREATING APPARATUS.

Application filed October 22, 1924. Serial No. 745,261.

To all whom it may concern:

Be it known that I, FRANK R. MILLER, a citizen of the United States of America, residing at Troy, county of Miami, and State of Ohio, have invented certain new and useful Food-Treating Apparatus, of which the following is a full, clear, and exact description.

The present invention relates to food 10 treating apparatus and particularly to apparatus having a roller or the like for working, crushing, or otherwise treating food-stuffs.

One of the principal objects of the present 15 invention is to provide such an apparatus having simple means for retaining the roll in position on its supporting shaft, said means being easily operable to release the roll for cleaning or replacement.

Another object is to provide yielding 20 means for pressing the roller to its work, said yielding means cooperating in retaining the roll in position on the roller shaft.

Other objects and advantages of the invention 25 will be apparent from the following description taken in connection with the accompanying drawings, in which:

Fig. 1 is a side elevation, partly in section, 30 of the present invention, parts of the food treating machine being indicated to show the relation of the present invention thereto;

Fig. 2 is an elevation similar to Fig. 1, the locking plate being raised to its unlocking 35 position and one of the rollers removed; and

Fig. 3 is a perspective view of the locking plate.

Referring to the drawings, 20 designates the food support of the machine; the support being herein shown as an apertured plate 40 although it will be understood that any other suitable form of support may be employed. The food to be treated is placed upon this food support 20 in position for the rollers to pass over it. Reference character 21 designates the driving shaft of the machine to the lower end of which is detachably secured a lower section 22 of driving shaft which, as shown, is provided with an enlargement to 45 form a shoulder 23, the enlargement being provided with a socket 24 to receive the driving shaft 21. The shaft 21 is secured in the socket 24 by means of a bayonet slot connection 50 or any other desired form of connection.

Longitudinally slidable upon the lower part of the driving shaft 22 is a head 26 carrying transversely disposed roller shafts 27 which constitute bearings for the rollers 28. A laterally extending pin 29 carried by the driving shaft 22 engages the downwardly opening slot 30 formed in the head 26 thereby transmitting rotary driving force from the shaft 22 to the head and rollers. Pin 29 also limits the downward movement of the head and rollers on the driving shaft 22 and prevents the same from falling off the shaft 22 when the latter is removed from the machine.

The inner ends of the rollers 28 are provided with bosses or extensions 35 to which are secured annular flange rings 36. A locking plate 37 which is longitudinally slidable upon the driving shaft 22 is provided at its ends with down-turned lips or flanges 38 which are adapted to overlie the annular flanges 36 of the rollers so as to retain the rollers in position on the roller shafts 27. A coiled spring 40 interposed between the locking plate 37 and the shoulder 23 on the shaft 22 yieldingly holds the locking plate in its proper position to lock the rollers 28 against endwise removal. A spacer or sleeve 41 is interposed between the locking plate 37 and the head 26 to prevent the locking plate 70 from being pressed into direct contact with the roller flanges 36, and also to transmit the pressure of the spring 40 to the head 26 thereby yieldingly pressing the head and the rollers towards the food support 20. While the spacing sleeve 41 has been illustrated as separate from the head 26 it is apparent that it is functionally part of the head and it may therefore be made as an integral part thereof.

In the normal operation of the machine the rollers 28 move over on through the foodstuffs on the food support or plate 20 and are yieldingly pressed towards the food support by means of the spring 41. This spring also retains the locking plate 37 in position to lock the rollers 28 upon the roller shafts 27 as illustrated in Fig. 1. The removal of the rollers for cleaning or replacement may be accomplished very easily and quickly by simply raising the locking plate as illustrated in Fig. 2, the flanges 36 of the rollers being then disengaged from the locking plate and the rollers being free to slide off the roller shafts 27.

While the form of apparatus herein described constitutes a preferred embodiment of the invention, it is to be understood that the invention is not limited to this precise 5 form of apparatus, and that changes may be made therein without departing from the scope of the invention which is defined in the appended claims.

What is claimed is:

- 10 1. In an apparatus for treating foodstuffs, a shaft member, a roller member pivotally supported thereon, and means for retaining the roller on said shaft, said means comprising an annular flange carried by one of said members and a yielding hook member carried by the other member and adapted to cooperate with said flange.
- 15 2. In an apparatus for treating foodstuffs, a shaft, a roller pivotally supported thereon, and means for retaining the roller on said shaft, said means comprising an annular flange carried by the roller and a yielding hook member connected with the shaft and adapted to hook over said flange.
- 20 25 3. In an apparatus for treating foodstuffs, a shaft, a roller pivotally supported thereon, and means for retaining the roller on said shaft, said means comprising an annular flange carried by the roller, a locking plate 30 movable in a direction transverse to said shaft and adapted to cooperate with said flange to lock the roller on said shaft, and yielding means for holding said locking plate in locking position.
- 35 4. In an apparatus for treating foodstuffs, a shaft, a roller pivotally supported thereon, and means for retaining the roller on said shaft, said means comprising an annular flange carried by the roller, a locking plate 40 movable in a direction transverse to said shaft and adapted to cooperate with said flange to lock the roller on said shaft, yielding means for holding said locking plate in locking position, and stop means for holding said locking plate out of contact with said annular flange.
- 45 5. In an apparatus for treating foodstuffs, a central support, a plurality of shafts carried thereby and extending laterally therefrom, a roller pivotally supported on each of said shafts, and a common centrally disposed means for retaining said rollers

against outward movement along their shafts.

6. In an apparatus for treating foodstuffs, 55 a central support, a plurality of shafts carried thereby and extending laterally therefrom, a roller pivotally supported on each of said shafts, and a common means for retaining said rollers on their shafts, said means being yieldable to permit the ready removal of said rollers.

7. In food treating apparatus having a food support, a rolling device comprising a roller adapted to roll over said support, a 65 roller shaft for pivotally supporting the roller, means for moving the roller over said support, and common means for yieldingly pressing the roller toward the support and for retaining the roller on its supporting 70 shaft.

8. In food treating apparatus having a food support, a rolling device comprising a rotatable drive shaft, a head connected for rotation with said shaft and longitudinally 75 slidably thereon, a transverse roller shaft carried by the head, a roller rotatably supported upon the transverse shaft and adapted to roll over said food support, yielding means engaging said head for pressing the head and roller towards the food support, and means interposed between the yielding means and said head and adapted to cooperate with the roller to retain the latter in position on the roller shaft. 85

9. In food treating apparatus having a food support, a rolling device comprising a rotatable drive shaft having a shoulder thereon, a head connected for rotation with said shaft and longitudinally slidably thereon, a transverse roller shaft carried by the head, a roller rotatably supported upon the transverse shaft and adapted to roll over said food support, a locking plate slidably mounted on the drive shaft and normally in engagement with said head, the locking plate having means thereon for engaging the roller to retain the latter in position on the roller shaft, and spring means interposed between the shoulder on the drive shaft and the locking plate. 90 95 100

In testimony whereof I hereto affix my signature.

FRANK R. MILLER.
